[57] CLAIM

The ornamental design for a packaging container for a
pharmaceutical vial, as shown and described.

DESCRIPTION

FIG. 1 is a perspective view of a packaging container
for a pharmaceutical vial showing my new design;
FIG. 2 is a side elevational view, the views from the
left, right and opposite sides being the same in appear-
ance;

FIG. 3 is a top plan view, the bottom plan view being
the same in appearance, and

FIG. 4 is an exploded perspective view thereof.
